UNITED STATES PATENT OFFICE.

JOSEF KLEIN, OF DRESDEN-LOSCHWITZ, GERMANY.

ADVERTISING APPARATUS.

Application filed September 14, 1925, Serial No. 56,313, and in Czechoslovakia October 2, 1924.

This invention relates to an advertising apparatus designed to attract the attention of the public. This apparatus which is preferably displayed in show windows is at the same time a price indicator and an entertainment, its object being to attract the attention of passers-by and to detain them for the duration of a musical or acoustic display, so that the advertisements are brought to the notice of the people and a disposition is created to purchase the advertised goods.

The advertising apparatus according to the invention consists of a kiosk-like casing and of a tower-like top piece to which from a motor a rotating movement and a reciprocating movement in vertical direction are communicated. From the same driving motor other mechanical apparatus are operated which serve to execute musical performances and to display advertising cards or boards. On the side walls of the casing and on the top-piece advertisement-cards are arranged, which may be transparent and lighted from a source of light arranged within the casing.

An embodiment of the invention is illustrated, by way of example, in the accompanying drawings in which

Fig. 1 is a perspective view of the complete apparatus.

Fig. 2 shows in vertical section the casing and the driving mechanism in the same.

Fig. 3 shows a casing with a moving figure.

This apparatus includes a kiosk-like casing 1 having advertising cards 2 on its upper edge and a tower-shaped top piece 3. In the casing 1 a mechanical driving motor 4, for instance a spring motor or an electric motor to be switched in by means of plug contacts, is arranged. The motor 4 drives a shaft 5 and has a propeller 6 serving as fan to cool the air in the casing. A gear wheel 7 on shaft 5 rotates a worm wheel 8 keyed on the end of shaft 9 of the top piece which projects into the casing. This shaft 9 of the top piece has a slot 10 with which a catch pin 11 engages which is fixed on the worm wheel 8. The worm wheel 8 is located between two abutments 12 and 13. The shaft 9 is thus rotated but at the same time adapted to be moved in vertical direction of the length of the slot 10. With this object in view a tooth 14 on shaft 9 is intermittently raised by a cam disk 15 on shaft 5, a spring 16 serving to return the shaft 9 and conse-

quently the top piece 3 into the normal position. The top piece is thus continuously rotated and intermittently raised and lowered so that advertising boards, flags and the like on the top piece are made to move to attract the attention of the passers-by. A vertical rod 17 mounted on the top plate of casing 1 has at its lower end an arm 18 acted upon at regular intervals by the cam disk 15 on shaft 5 or by other cam disks on said shaft so that it is raised and then lowered again by the action of a spiral spring 19, bells or other musical instruments mounted on said rod 17 being thus made to sound. There may be arranged on the top plate of the casing any desired numbers of bells or the like, one separate cam wheel or pin being provided on shaft 5 for each bell.

Any convenient musical instrument, arranged in the casing or under the casing may be operated from shaft 5.

In at least one side wall of the casing a window 20 is provided for the display of the representation of a human figure 21. One arm of this figure carries a flag in the national colors or bearing advertising matter, and this arm 22 is fulcrumed on the body portion at 23 to swing in front of the figure. A lever arm 24 extends from this arm and is articulated at its outer end 24 to a strap 124 of an eccentric 25, which latter is actuated from the main drive shaft 5 in any suitable manner, for instance, as shown, by a belt drive 125.

I claim:

1. In an advertising device of the character set forth, in combination, a casing presenting a window in at least one of its side walls, a motor in said casing, a drive shaft driven from said motor, an actuator fixed on said shaft, a rod supporting advertising means disposed partly within and partly without said casing and operable by said drive shaft in continuous rotary and intermittent axially reciprocatory manner, audible means axially guided in said case and jar-operated by said actuator, and a representation of a human figure displayed in the casing window, one arm of said figure bearing advertising means and being articulated to the body, and means operated by said drive shaft for swingingly actuating said arm.

2. In an advertising device in accordance with claim 1, means for actuating the reciprocatory and rotatable rod in its com-

compound movements, comprising, the rod presenting a guide slot in its inner end portion, a drive shaft, a worm thereon, a worm wheel meshing with said worm and loosely riding on said rod, a pin extending from said worm wheel for slidable cooperation with said rod slot, means for holding said worm wheel stationary relative to the rod reciprocations,

a pin laterally extending from said rod, and an actuator on said drive shaft for periodic cooperation with said rod pin for lifting said rod once for each complete shaft revolution.

In testimony whereof I affix my signature.

JOSEF KLEIN.
